his Attorney.

UNITED STATES PATENT OFFICE.

ARTHUR H. SWEETLAND, OF LONG BEACH, CALIFORNIA; INEZ SWEETLAND EXECUTRIX OF SAID ARTHUR H. SWEETLAND, DECEASED.

HAND DRILL.

1,411,538.

Specification of Letters Patent.

Patented Apr. 4, 1922.

Application filed October 20, 1919. Serial No. 331,864.

To all whom it may concern:

Be it known that I, ARTHUR H. SWEETLAND, a citizen of the United States, residing at Long Beach, in the county of Los Angeles, State of California, have invented new and useful Improvements in Hand Drills, of which the following is a specification.

This invention relates to hand drills, the prime object being to provide a small compact drill which may be used in the place of breast drills and in situations where space is limited and there is not enough room to use the ordinary breast drill; and my hand drill comprises primarily a device made in "pistol form" with a pistol grip, lubricating means, cooling means, switch means which may be easily turned on and off; making a device which may be used with great efficiency.

The device consists mainly of a pistol shaped case which holds an armature shaft which in turn is geared to a chuck in which drills may be set. On this armature shaft I mount a cooling fan which sucks air from openings in a protected position in the lower part of the case, around the motor armature, the fan being mounted in such a manner on the inside of the case that it is impossible to catch the fingers therein.

The device is made so that the user can get a good firm hold on the pistol grip, the button for the switch being directly above the grip and adapted for operation by the thumb. The chuck is mounted in direct line with the hand grip, so that the applied force is in line with the drill at all times. This is one of the important features of my invention. The motor shaft extends out at one end so that a grinding wheel may be mounted thereon, and for other purposes as hereinafter described.

I will describe a preferred form of my invention in detail, referring to the accompanying drawings, in which—

Fig. 1 is a side elevation of my device; Fig. 2 is a vertical central longitudinal section thereof; Fig. 3 is a horizontal section taken on line 3—3 of Fig. 2; and Fig. 4 is an end elevation of the device.

In these drawings the numeral 10 designates the case in which my device is mounted, and 11 the hollow pistol grip. Armature 13 is mounted on shaft 14 which revolves in bushings 15 and 16, as is best

shown in Fig. 2. On shaft 14 I place pinion 17 which meshes with large gear 18 mounted on chuck shaft 19 supported in bearing 20 at the lower forward end of the case. These gears are sized in such proportion that the chuck shaft will turn from 500 to 900 R. P. M. depending on the pressure on the pistol grip and the size of the drill. The drill chuck 22 is mounted on shaft 19 in any ordinary manner.

On the rear end of armature shaft 14 I place fan 24 which has for its function the cooling of the whole device. Air holes 25 are placed on the forward lower side of the case behind the gear case 10^a. Turning of the shaft 14 revolves the fan 24 which sucks air through the air holes 25, around the armature and forces it out through hollow handle 11 and through openings 26 at the back of the case. These air holes 25 are placed in such a position on the case that it is impossible for dirt to fall into the case. By this means I keep my device cool and also keep the inside of the case clean. The fan rotates in such a direction that it will push the fingers out if they happen to be inserted through openings 26.

Oil holes 27 and 28 are provided for the oiling of the two shafts 14 and 19.

End thrust of the chuck shaft is taken by a simple end thrust bearing. This may be in the form of a hard steel ball 41 set in a socket 42 in the wall of gear case 10^a, the end of the shaft bearing against the ball, one side of which may be flattened slightly for that purpose.

Electrical connection is made through cable 30 to contact 31; and the circuit is closed by pressing on push button 32 which shoves push rod 30 forward until contact 34 presses against contact 31. A flat spring 35 tends to hold contact 34 away from contact 31 when the device is not in use. The switch is connected to the motor in the usual manner. The motor is preferably a series wound D. C. motor that will operate either on direct or alternating current. Through the cable 30, the drill may be attached to any source of electricity.

Armature shaft 14 projects forward at 10^b for the purpose of mounting a small grinding wheel, if desired; and for the purpose of carrying a collar or disk 40; by means of which the shaft 14^b and chuck shaft 19 may be held from turning when 110

the chuck is being set or loosened—the chuck being operated by rotation. The fact that gear 17 is smaller than gear 18 facilitates this operation; shaft 14 being easily held 5 from rotation. The gear ratio in the specific case here described is 6 to 1.

The drill here described and illustrated (the drawings are full size) successfully 10 operates drills up to one-quarter inch and 15 does fast work. It is easily handled; the grip is natural—the palm of the hand comes in a direct axial line back of the drill axis, and the fingers clutch the motor case while the thumb presses against the push button 20 and against the case. The grip is naturally firm. Due to all these features the drill is easily and accurately held in proper alignment, and breakage of drills due to un- 25 steady holding is very small. If it is de- 30 sired to put more pressure on the drill the same may be used as a breast drill.

From the foregoing it will be seen that I have provided a hand drill simple and compact in character, and one that may be used 25 with great efficiency in limited spaces. The hand is in a direct line with the chuck and drill and the push button in a convenient place. The oiling and cooling systems are 30 efficient and simple; and the drill is of light weight. The casing may be of aluminum.

It will be understood that my device may be modified in detail of structure and arrangement without departing from the features herein typified; and also that it may 35 be used for specific purposes not herein mentioned. Such variations I do not exclude, except as specifically stated in the following claims.

Having described a preferred form of my 40 invention, I claim:

1. The combination of a motor casing, a handle at the rear end and extending to one side of the casing, whereby the casing may be supported by one hand with the fingers 45 thereof engaging both the handle and body of the casing, and the palm bearing against the back of the handle, a motor within the casing, a chuck shaft journaled in the casing on an axis between the motor axis and the 50 side of the casing beyond which the handle projects, so that longitudinal pressure exerted on the handle by the palm of the hand supporting the tool will be in substantial alignment with the chuck shaft and the center of mass of the casing and motor is at one 55 side of the axis of the chuck shaft, and driving connections between the motor and chuck shaft.

2. The combination of a motor casing having 60 approximately the form of a pistol

adapted to be held in one hand with the fingers grasping the body and the palm bearing against the handle thereof, a motor within the casing above and forward of the handle, a chuck shaft journaled in the forward end of the casing on an axis below the motor and in alignment with the portion of the case against which the operator's palm bears, gearing connecting the chuck shaft and motor at the forward end of the casing, 65 and a supplemental case for said gearing extending below the main case.

3. The combination of a motor casing having at its rear end a handle that extends laterally beyond one side of the casing whereby the latter may be supported by one hand with the fingers thereof engaging both the handle and body of the casing and with the palm bearing against the back of the handle, a motor within the casing, a chuck 75 shaft journaled in a bearing supported by the front end of the casing, said shaft extending forward from the casing and in substantial alignment with the portion of the handle against which pressure of the palm 80 of the operator's hand supporting the tool is exerted, and gearing connecting the motor and chuck shaft.

4. In a hand drill or the like, a case carrying a motor, the shaft thereof extending beyond one end of the casing, a chuck shaft journaled in the case and geared to the motor to run at a speed lower than motor speed, a chuck on the shaft adapted to be set and loosened by revolution relative to the shaft, 90 and a thumb wheel on the projecting end of the motor shaft which may be grasped to hold the motor shaft and chuck shaft stationary while rotating the chuck.

5. The combination of a motor casing having approximately the form of a pistol adapted to be held and supported in one hand with the fingers grasping the body of the casing and handle and the palm bearing against the handle thereof, a motor within 100 the casing, a chuck shaft journaled in the casing and extending forwardly therefrom, gearing connecting the chuck shaft and motor, and a switch controlling movement of the motor mounted on the rear of the body 105 of the casing above the handle portion thereof in position to be operated by the thumb of the hand supporting the casing.

In witness that I claim the foregoing I have hereunto subscribed my name this 18th 110 day of October, 1919.

ARTHUR H. SWEETLAND.

Witness:

VIRGINIA I. BEINGER.
